NEWTON F. McKEON, OF PATERSON, NEW JERSEY.

FOUNTAIN-PEN.

1,088,691.

Specification of Letters Patent.

Patented Mar. 3, 1914.

Application filed August 24, 1912. Serial No. 716,923.

To all whom it may concern:

Be it known that I, THEODORE K. FELCH, a citizen of the United States, residing at Newark, in the county of Essex and State of New Jersey, have invented a new and useful Fountain-Pen, of which the following is a specification.

The present invention relates to improvements in fountain pens.

10 The primary object of the invention is the provision of a fountain pen, in which the old style carrying barrel is employed only as a handle, while the ink reservoir is made in the form of a tube connected to and carried through the medium of a coupling by the pen head, the same being bodily removable therewith and made of such material as visually to display the contents, so that the writer may ascertain in an instant the quantity of ink within the reservoir, the barrel or handle being frictionally engaged so that the same may be readily removed without disturbing the ink or soiling the fingers.

25 A further object is the provision of a fountain pen in which the coupling sleeve, which is interiorly threaded at one end and provided with a reduced portion at the other end, carries a transparent ink reservoir or tube, the open end of which is disposed toward the interiorly threaded portion and in co-active relation with the removable pen head, the latter being carried by the coupling, so that the removal of the coupling with the pen head from the barrel or handle, which is so constructed as to be free at all times of ink, will permit the writer quickly to ascertain the amount of ink in the reservoir without soiling the fingers.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete pen with the cap in handle position. Fig. 2 is a similar view with the barrel separated from the pen head and ink reservoir. Fig. 3 is a longitudinal sectional view through the barrel, coupling

sleeve, ink reservoir and cap, the pen head 55 being in elevation; Fig. 4 is a section taken on line 4—4 of Fig. 3.

Referring to the drawings, the numeral 1 designates the coupling sleeve, which as shown is provided with the reduced and 60 tapered nipple 2 at one end and with the threaded counterbore 3 in the other end, the bore 4 of the sleeve being slightly enlarged next inside the counterbore as at 5. Fitting snugly through the bore of the coupling 1 65 and extending beyond the nipple 2 thereof is a transparent ink reservoir or tube 6, whose rim or mouth 7 is slightly flared to fit snugly within the enlarged portion 5 of the bore 4 of the coupling, so that the tube 70 6 will be held within the coupling to be bodily carried thereby. In assembling the tube and coupling, the closed end of the tube is slid through the coupling 1 until the mouth of the tube enters the counterbore 3, 75 and then the threaded nipple or stem 8 of the pen head or section 9 is threaded into the counterbore 3 of the coupling 1, which will force the tube 6 home so as to anchor it within the coupling. By this means it 80 will be seen that the pen head may be readily removed to permit of the filling of the transparent tube 6, and thus said tube 6 is at all times bodily carried by the pen head 9.

85 In order to properly incase the projecting end of the transparent tube 6 and form a handle for the pen, the tubular barrel 10 has its enlarged mouth 11 slipped frictionally over the reduced end 2 of the coupling 90 1, so that the barrel 10 houses the tube 6 loosely, the bore of the sleeve being relatively smaller in diameter than that of the barrel.

A pen cap 12 of usual construction is 95 provided and is readily engageable with the pen head 9 or with the lower end of the barrel 10, all as clearly shown.

The glass tube 6, may also be vulcanized, cemented or otherwise made fast within the 100 coupling 1, and not held in by the pen head 9; and in fact the cementing method may be found to be preferable.

Attention is directed to the fact that when the pen section 9 is engaged to the sleeve 1, 105 the nipple 8 of the pen section will serve to seat or force the flared mouth of the reservoir against the enlarged or tapered

portion of the sleeve bore. This is of advantage inasmuch as the reservoir is thus anchored within the sleeve in a highly desirable and efficient manner, it being noted that the reservoir cannot be withdrawn from the sleeve, when the barrel is detached from the sleeve to expose the inner end of the reservoir.

From the foregoing description, it is evident that with a fountain pen constructed according to the present invention, that a means for determining the quantity of ink within the reservoir is readily accessible, it simply being necessary to detach the barrel 10 which is connected to the coupling sleeve 1 by a friction joint, thus disclosing the transparent tube 6, which preferably being made of glass, will at a glance indicate the quantity of the ink within the same. By 20 this means it will also be seen that the annoyance of soiling the fingers in disconnecting the pen head for ascertaining the quantity of ink within the reservoir 6 is obviated.

What is claimed is:

A fountain pen embodying a sleeve having a threaded counterbore at one end, a barrel having its mouth detachably engaged to the other end of the sleeve, the sleeve bore being tapered next inside the counterbore, a transparent tubular ink reservoir fitting snugly through the sleeve bore and having its closed end housed within the barrel, the mouth of the reservoir being flared and fitting snugly in the tapered portion of the sleeve bore, and a pen section having a reduced nipple threaded into the said counterbore to seat the flared mouth of the reservoir against the tapered portion of the sleeve bore.

In testimony that I claim the foregoing as my own, I have hereto affixed my signature in the presence of two witnesses.

THEODORE K. FELCH.
